Application May 14, 1928, Serial No. 277,772

23 Claims. (Cl. 121—142)

This invention relates to steam engines and more particularly to a method of an apparatus for equalizing or smoothing out the torque in such engines, and, since it is particularly useful in and applicable to locomotives, it will be herein described and illustrated in connection with locomotive construction and operation.

The objects and advantages of the invention will be better understood if certain practical considerations in connection with this art be first set forth.

In multi-cylinder reciprocating engines there is not only the irregularity or inequality in net torque or rotative effort resulting from the constant change in thrust of each piston of the engine from zero to maximum, but there are also inequalities as between the several torque peaks themselves in each complete cycle of the engine, which arise largely from the differences in angular position of the connecting rods in the several quarters of the cycle. For example, in a two cylinder engine, with cranks set at the usual 90° angle to each other, there are (in the combined rotative effort curve) four maximum and four minimum, i. e. high and low points, or torque peaks and valleys, in each cycle of the engine's operation, but these peaks are not the same. The highest quarterly maximum peak occurs during that quarter of the cycle when the leading cylinder is working on the head end and its crank is in the first quarter revolution from its forward center, and the following cylinder is working on the crank end and its crank is in the last quarter revolution toward its forward center.

If the foregoing quarter cycle be termed the first quarter, and the other quarters be numbered thereafter in succession, the lowest quarterly maximum torque peak occurs in quarter number 3, and the intermediate maximum peaks in the second and fourth quarters, the second peak ordinarily being slightly higher than the fourth. The differences between the several minimum torque peaks, i. e., low torque points, are not so great. In locomotives, such torque inequalities result in a tendency of the driving wheels to start slipping at the peaks, particularly at the highest peak, and once having lost their adhesion to the rails they are apt to spin until the throttle be closed and a fresh start made. Furthermore, at the valleys or minimum points of the torque curve, a locomotive is often incapable of starting a load which it could easily handle when once started. This frequently necessitates the taking of slack with consequent rough handling of trains in starting.

In connection with locomotive calculations the factor of adhesion ordinarily used takes into consideration the average tractive power developed during a revolution of the drivers. However, the starting power which a locomotive can actually deliver is governed by the true factor of adhesion which takes into consideration the maximum power, i. e., the highest torque peak, that may be developed during a complete revolution. Heretofore, in order to increase the average starting power, resort has been had either to the expedient of adding drivers to the engine, or else to increasing the weight on the drivers which allows an increase in the power which can be applied without making the engine more slippery, but with modern locomotives the number of drivers and the weight per driver has about reached the practical limit. It is partly to overcome this difficulty that the three cylinder engine has been introduced, with its increased overlapping of piston thrusts, but even the use of three cylinders will not obviate substantial differences between the peaks of the torque curve.

We propose, by our invention, to increase the average starting power of a locomotive by reducing the factor of adhesion, and this without making the engine more slippery. In fact, by our invention, an increase in the average starting power can be obtained with less tendency to slip than before; or in other words, the true factor of adhesion can actually be increased while what is normally termed the factor of adhesion is being reduced. We accomplish the desired result, and overcome to a large extent the difficulties and disadvantages hereinbefore set forth, preferably by smoothing out the rotative effort curve of the locomotive while maintaining the true factor of adhesion constant, thus lowering what is ordinarily termed the factor of adhesion.

In other words we aim by our invention to smooth out the peaks of the rotative effort curve and bring them more nearly in line with the average rotative effort, which makes it possible to increase the said average rotative effort without rendering the engine more slippery.

Furthermore we aim by our invention to improve the operation both of two-cylinder and three-cylinder engines, and to provide simple and reliable mechanism whereby the desired advantages can be easily and inexpensively attained in existing equipment.

More specifically our invention contemplates the provision of irregular steam distribution as between the two ends of a cylinder, and/or as between different cylinders of an engine, as for

example by alterations in the cut-off of the valves, in order to obtain a smoother rotative effort curve.

How we accomplish the foregoing objects and advantages, and such others as are incident to our invention or will appear to those skilled in the art, will be evident from the following description, reference being had to the accompanying drawings, in which:

10 Fig. 1 is a graph illustrating the improvement in the rotative effort curve of a two-cylinder locomotive embodying our invention;

Fig. 1a is a similar graph of the operation of the same locomotive when running in reverse motion;

Fig. 2 is a graph similar to Fig. 1, but of another rotative effort curve;

Fig. 3 is an enlarged longitudinal vertical section through the right-hand of a locomotive 20 valve chest illustrating a cam-operated poppet valve mechanism adapted to carry out the invention;

Fig. 4 is a section taken on the line 4—4 of Fig. 3.

25 Fig. 5 is a diagrammatic illustration, viewed from the right-hand side of the locomotive, of certain control mechanism used in connection with the construction shown in Figs. 3 and 4;

Fig. 6 is an enlarged view, partly in section 30 and partly in elevation, of the admission valve cam of Figs. 3 and 4;

Fig. 7 is a perspective view of the cam, showing a shiftable cam element located out of its normal position in order to illustrate the contours of the parts;

Fig. 8 is a vertical section through one of the control valves of Fig. 5; and

Fig. 9 is a condensed left-side elevational view of a two-cylinder locomotive on which the mechanism of this invention has been applied, certain parts being shown somewhat diagrammatically.

Referring first to the graphs, it will be seen that in Fig. 1 we have shown the rotative effort curve of a two-cylinder locomotive having 50% limited cut-off, through one complete cycle. The numerals at the left of the figure indicate rotative effort, in thousands of pounds, and those at the bottom the degrees of rotation of the drivers. The crank pin positions are indicated at the top, rotation being clockwise, as shown by the arrow, and the right (leading), and left (following), sides of the engine are indicated by the characters RS and LS, respectively. The lines RC and LC are curves indicating the torque exerted through the right cylinder and crank and left cylinder and crank, respectively, and the curve above these two indicates the total torque, i. e., the combined rotative effort.

60 It will be seen that the mean average torque or rotative effort, in this example, with a valve cut-off of 50% for both ends of each cylinder, is 60,000 lbs., but the torque peaks vary greatly, not only from this average, but also as between 65 themselves, the highest maximum torque peak 1, being about 72,000 lbs., which is 19.7% above the mean average, while the other high torque peaks, 2, 3 and 4, are approximately 67,000, 59,000 and 65,000 lbs., respectively. By altering 70 the cut-off, in accordance with our invention, to 43% on the crank end of the left (following) cylinder, and to 60% on the head end of the same cylinder, as indicated on the graph, the highest peak 1 is lowered to about the height of peak 2, and the lowest high peak 3 is raised to

about the height of peak 4. As for the minimum or low peaks, while peak 5 remains the same and peak 8 is lowered somewhat, peaks 6 and 7 are both raised. The improvement, in the lowering of the high peak and the raising of the minimum peak and two of the valleys in the curve, is graphically shown by the shaded areas. The net change in the average rotative effort is a rise to the line a, an increase of about 1500 lbs., and with less tendency to slip.

10 It will now be seen that along with a rise in two of the low peaks and an increase in the average rotative effort the highest maximum peak has been reduced from 19.7% above mean to about 9.6% above mean. Added power could 15 now be applied to the cylinders to such an extent as to raise the mean rotative effort to approximately 66,500 lbs., that is, until peak 1 again reached 72,000 lbs., without rendering the engine any more likely to slip than it was originally.

20 By reference now to Fig. 1a, it will be seen that we have illustrated the operation of the same locomotive, when moving in reverse, and when employing the preferred embodiment of our invention (as hereinafter described). It 25 will be readily understood (as later pointed out in detail) that when a two-cylinder, reciprocating-engine, locomotive is reversed, the leading side becomes the following side and the following side becomes the leading side, considered with 30 reference to the direction of rotation of the crank pins, with a pin on one side of the locomotive leading a pin on the other side by 90°. Similarly to the graph of Figure 1, the graph of Figure 1a shows, in a solid line (near the top of the figure) 35 the combined rotative effort curve of a two-cylinder locomotive with 50% cut-off at each end of each cylinder, but with the locomotive running in reverse; and showing in dotted lines the modification of that curve by the reversed 40 operation of the preferred embodiment of the present invention.

For convenience of comparison between Figure 1 and Figure 1a, the progression of the graph of Figure 1a has been made to read from left to right, as in the case of Figure 1, and the initial crank pin positions (marked RS for right side and LS for left side) are located the same as in Figure 1, that is, with the right crank pin on forward dead center, but the direction of rotation 45 is in a sense opposite to that of Figure 1, that is, 50 counterclockwise, as indicated by the arrow.

55 Since the right cylinder and crank were assumed to be leading in Figure 1, it is obvious that the left cylinder and crank will be leading in Figure 1a. Now it is clear that since the modified cut-off on the left cylinder of Figure 1 and the uniform cut-off on the right cylinder thereof produce the illustrated improvement in forward motion, those relationships must be reversed for 60 reverse motion, if the locomotive is to have the same advantages when operating in reverse as when moving forwardly. Portions of the mechanism later described have been devised to accomplish this reversed modification of the cut-off, and in accordance therewith the graph of 65 Figure 1a shows the left crank torque curve for 50% cut-off operation (marked H E for the head end stroke, and marked C E for the crank end stroke), while the curve for the right-hand 70 crank shows in dotted lines the modification obtained by 60% cut-off on the head end stroke and 43% cut-off on the crank end stroke.

75 The shaded areas show the improvement in the raising of the lowest torque peak and asso-

ciated depressions of the combined rotative effort curve, and the reduction of the highest torque peak thereof; the improvement thus being similar to that shown in Figure 1, and similarly illustrated, the modification of the curve being indicated by the dotted line portions. The net change in the average rotative effort is a rise to the line *a*, an increase of about 1,500 lbs., just the same as in forward motion which was 10 illustrated in Figure 1.

From the above comparison of Figures 1 and 1a it will be observed that the normal curve produced at the left crank, in reverse (Figure 1a) is substantially the same as the normal curve 15 at the right crank in forward motion (Figure 1); and that the normal and modified curves at the right crank for reverse (in Figure 1a) are substantially the same as the normal and modified curves of the left crank for forward motion (in 20 Figure 1); and that the net results, i. e., improvement in the combined rotative effort curve, are substantially alike in reverse (Figure 1a) as in forward motion (Figure 1); when our invention is functioning in its reversed relationship, according to the direction of motion of the locomotive. There is, however, one major distinction, namely: the benefits from the altered cut-off occur between approximately 0° and 90° and between 180° and 270°, in the forward motion 25 (Figure 1), that is, they occur substantially in the first and third quarters of a cycle commencing with the right side crank at forward dead center (forward with respect to the locomotive), whereas in reverse the same improvements occur 30 in the second and fourth quarters of the cycle, commencing from the same point, that is, with the right side crank at forward dead center (forward with respect to the locomotive). It might 35 here be noted that below the graph of Figure 1a we have indicated the degrees of rotation, separately as to the right crank and the left crank, identifying a given point in the cycle by the same degree number as employed in Figure 1, but reading in the reverse order, since the direction of rotation is opposite.

From the foregoing explanation of Figure 1 and Fig. 1a the other graph will also be readily understood. The graph of Figure 2 illustrates the results obtained with a 90% cut-off, two-cylinder engine, in which the crank end of the 40 left cylinder has been altered to a 70% cut-off. In this case the highest peak 1, has been reduced from 23.6% above mean to 16.3% above mean, which is about the same as peak 2. An increase 45 in power could now be applied to this engine sufficient to increase the average rotative effort by about 8,000 lbs. with no greater tendency to slip than before the alteration in the cut-off.

In applying the invention to a two-cylinder locomotive engine we have provided an oscillating-cam-operated poppet-valve apparatus. The poppet valve device, while herein shown merely for illustrative purposes—other valve devices being applicable—has the advantage of 50 full opening of the ports even at short limited maximum cut-offs.

Referring now to the illustrative embodiment, Figs. 3 to 9 inclusive, it will appear that we have devised a modified form of Lentz valve mechanism, arranged to carry out the invention on a two-cylinder engine. Figs. 3 to 8 illustrate the construction for the right hand side of the engine, (embodying in this instance the following crank); while Fig. 9 shows the locomotive from 55 the left-hand side (having the leading crank).

In this construction the usual valve rod connection 15 is made to the arm 16a of cam-shaft 19 which extends into the valve chest 17. This shaft carries the usual exhaust-valve cam 20 controlling the exhaust through outlet 21, which is thus oscillated by the usual valve motion mechanism (a known example of which is shown in Fig. 9) in a manner known in the art, which will not here be enlarged upon. Pipe 18b is the usual lubricator pipe for cylinder 18a.

The admission-valve cam 22, also carried on shaft 19, controls the admission of steam through inlet 23 and steam chamber 24, by means of the annular poppet valves 25, 26, controlling ports 27 and 28, respectively, at the two ends of the cylinder 18a. These valves, as ordinarily used, are slightly overbalanced for closing, and in addition have adjustable springs 25a and 26a to insure seating when steam is entirely cut off from the steam chamber 24, as when the engine is drifting. The valves are controlled by cam 22 through the intermediation of their respective stems 29, 30, and cam-engaging rollers or followers 29a, 30a.

Cam 22 has not only the usual high and low surfaces 31, 32, with intermediate sloping surfaces 33 and 34, each of the latter of which in the ordinary construction controls both the admission and cut-off for its particular end of the cylinder, but in our construction this cam is also equipped with additional cam elements comprising two movable segments 22a and 22a', mounted on bars 22c slideable in guides 22b, providing additional cam surfaces 31a, 31a, and slopes 33a and 34a respectively.

Upon oscillation of the cam assembly, by means of the ordinary valve motion, in timed relation to the piston stroke, the cam slopes 33 and 34a control the cut-off and slopes 33a and 34 the admission of valves 25 and 26, when the movable segments 22a and 22a' are operating. At times when the movable segments are not operating, the cut-off and admission are both controlled by slope 33a for valve 25, and by slope 34 for valve 26, thus giving substantially 45 equal admission and equal cut-off for the two ends of the cylinder.

In the ordinary Lentz construction, the surface 33a is a fixed part of cam 22 and normally controls both admission and cut-off through valve 25 and port 27; and surface 34 controls the admission and cut-off through valve 26 and port 28, either valve being wide open when its cam follower rides on cam face 31, and entirely closed when its follower rides on face 32. In our construction, on the other hand, where a later cut-off is desired on the head end of the cylinder (i. e., the "following" cylinder, as shown in Figs. 3 and 4) and an earlier cut-off on the crank end, the surface 34 is the admission point for valve 26, and the surface 33a the admission point for valve 25 while the surfaces 34a and 33 provide the requisite cut-off points, respectively, for the two valves. This is accomplished by the periodic shifting of the segments 22a and 22a' in their guide-ways causing surfaces 31a to shift into and out of registry with cam surface 31.

For the shifting of the cam segments, each is provided, at the respective ends of its sliding bar 22c with an inner and an outer beveled surface, 70 35 and 36, respectively, adapted to contact in alternation with co-operating beveled cam shifters 35a and 36a. When the segment 22a for the head end of the following cylinder (which is the segment shown at the right in Fig. 3) is 75

shifted inward i. e., toward the center line of the locomotive, by engagement of surface 36 with shifter 36a (see Figs. 3, 4, and 6), a bevelled cavity 37 on the under side of its bar 22c is engaged by a spring-pressed plunger 39 (see Fig. 6) to hold the segment in position inward, with its surface 31a out of line with the cam face 31 and follower 30a. Upon outward shifting of the segment by engagement of surface 35 with shifter 35a, a similar cavity 38 is engaged by the plunger 39 to position the segment in its operative position in line with the cam follower.

A similar shifting action takes place in the operation of the segment 22a' for the crank end of the following cylinder (which is the left hand segment shown in Fig. 3), but it should be particularly noted that this segment, as shown in dotted lines in Fig. 4, is mounted adjacent the outside end of its sliding bar 22c, so that when the segment is moved inward by its shifter 36a the surface 31a of segment 22a' will be in line with cam face 31 and the cam follower 29a, and when 22a' is moved outward by its shifter 35a its surface 31a will be out of line with face 31 and follower 29a.

In other words, the cam segment 22a at the right in Fig. 3, which is for the head end of the cylinder on the following side of the locomotive, when actuated by shifter 36a is moved inward, out of line with the fixed cam surface 31 (to the position shown in Fig. 6); while the cam segment 22a' at the left in Fig. 3, which is for the crank end of the cylinder, when similarly actuated by its shifter 36a is moved inward, into line with the fixed cam surface 31 (to the position shown in Fig. 4). Therefore, upon oscillation of the cam and the periodic shifting of the segments, surfaces 33a and 34 determine the admission points for the steam, and surfaces 33 and 34a the cut-off points, thus giving admission at the normal time at each end of the cylinder and giving a late cut-off and an early cut-off, respectively, at the head end and crank end of the cylinder. The result is, of course, the desired unequal steam, and consequently power, distribution as between the two ends of the cylinder, while approximately (though not exactly) equal or balanced distribution as between the two cylinders of the engine, in any complete cycle, is maintained.

For reasons which will hereinafter appear, each shifter member 35a is movable in guides 40, and is held outward or forward in operative position by a motor device comprising a piston 41 acted on by fluid pressure admitted to a cylinder 42 through a suitable pipe 43 (see Fig. 4). A spring 44 is provided to move the cam shifter 35a to inoperative position when the air or other fluid pressure is cut off from the cylinder 42.

Obviously, when the locomotive is running backward the following side becomes the leading side and vice versa. Since, in accordance with our invention, the leading side should have equal cut-offs at each end, the following side for forward motion must be altered to give equal cut-offs for reverse motion. Therefore, when running in reverse, the fluid pressure should be cut off from the cylinders 42 to permit the cam shifters 35a to move inward into inoperative position under the influence of their springs 44. Cam segments will then be moved inward by the fixed cam shifting faces 36a, the segment for the head end of the cylinder being held by its plunger 39 in the position shown in Fig. 6, and the crank end segment 22a' being held by its

plunger 39 in the central position shown in Figs. 4 and 7 with its surface 31a in line with cam surface 31, thus giving substantially equal cut-offs on both ends of the right cylinder, which is now the same as the left cylinder.

Fluid pressure should now be admitted to the motor devices 42 on the left (leading) side of the engine, which, for reverse, has become the following side, to give unequal cut-offs to the two ends of the cylinder on that side. The cylinder and valve structure for the left side of the engine, it should be understood, is similar to the structure hereinbefore described, and therefore the left side (see Fig. 9) is shown only in outline.

The air, or other fluid pressure, admitted to the cylinders 42, may be controlled in any suitable manner but we prefer to employ some means under the influence of the reversing mechanism of the locomotive, for example pilot valves 45, 46, actuated by movement of the locomotive reverse lever 47, as shown in Figs. 5, 8 and 9. Such pilot valves for controlling compressed air are well known in the art, and an example can be found in Peters Reissue Patent No. 16,483, dated November 23, 1926. In the arrangement here shown, when the reverse lever 47 is moved into forward position, the trip member 48 actuates the plunger 49 of pilot valve 45 (see Fig. 8) to open said valve and admit fluid pressure, from a suitable source of pressure, such as air tank 51, through pipe 52 and pipe 43R, to the pipes 43 (shown in Fig. 4) there being one such pipe for each motor cylinder 42, which actuates the pistons 41 to move cam shifters 35a into operative position. These shifters, together with shifter surfaces 36a, then cooperate with the cam segments 22a and 22a' to slide the latter back and forth, all as previously described, thus giving the cylinder the desired unequal cut-off as between its two ends.

When the reverse lever 47 is moved into reverse position, the member 48 is disengaged from plunger 49 to shut off the air supply and permit exhaust of the air from cylinders 42 on the right hand side of the engine, and engages plunger 50 of valve 46 to admit air through pipe 52a and pipe 43L to the cylinders 42 on the left hand side of the engine, which, as before said, when running in reverse, becomes the following side, (in our present example). The left side of the locomotive is shown fragmentarily in Fig. 9, with the various parts of our novel structure illustrated in their association with the ordinary running gear and valve motion mechanism. It might here be noted that the operating connection between the reverse lever 47 and the valve gear is illustrated only diagrammatically, as this may take any usual form, including, if desired, a power reverse gear. The left-hand piston, main rod and crank pin are indicated at LP, LR and LC; and the corresponding parts for the right side are diagrammatically indicated at RP, RR and RC.

In practice it may be desirable to have an irregular distribution of power only when the locomotive is working at late cut-offs, as in starting, and to have ordinary distribution when the engine attains higher speeds, whether operating forwardly or in reverse. We have therefore shown the trip 48 on the reverse lever as being comparatively short, so that when the reverse lever is taken out of the "corner", as it is termed, the pilot valve will close and exhaust the air out of cylinders 42, springs 44 will retract cam shifters 35a, and segments 22a and 22a' will move to their idle position, thus yielding substantially identical cut-offs between the ends of each cyl-

inder and between the cylinders. However, it is obvious that we may make the engaging arms of trip 48 of any desired length, so as to maintain the irregular distribution of steam even until 5 very early cut-offs, if desired.

From the foregoing detailed description of Figs. 3 to 9 inclusive, it will now be quite evident how we obtain the advantages illustrated in, and described with reference to, the graphs of Figs. 10 1 and 1a, which illustrate the forward and reverse operation of the locomotive. It will further be evident that the invention is particularly advantageous because the benefits from the 15 change in cut-off are obtained without the necessity of altering the normal crank angles and without any change in the other valve events, and further without altering the valve travel or port opening. In addition, by the control system employed, the modified cut-off can always be obtained on the "following" cylinder, whether operating in forward motion or in reverse; and a hooking back of the reverse lever after the locomotive gets under way automatically restores both 20 ends of both cylinders to equal cut-off, resulting 25 in the desired equality of power output at high speeds.

A portion of the benefit results from the earlier cut-off on the crank end of the following cylinder, and a portion of the benefit results from the 30 later cut-off on the head end of the following cylinder. Where the mechanism, as here shown, is capable of producing both these results, there is a very substantial improvement in the operation of the locomotive, and the steam pressure may 35 actually be stepped-up, if desired, without rendering the locomotive any more slippery than it was originally.

From Fig. 2, hereinbefore considered, it will be evident that it is possible to attain a portion of the 40 advantages of the mechanism even on a locomotive of very late cut-off when in full gear position (having, for example, a cut-off at 90% of the stroke), by providing an earlier cut-off at the crank end of the following cylinder.

45 In view of the foregoing it will be evident that, by an unequal steam, and consequently power, distribution, we obtain a marked improvement in the average rotative effort at slow speeds, so that the locomotive will have less tendency to 50 slip, or so that the average tractive effort may be increased substantially without any greater tendency to slip.

We claim:—

1. In engine mechanism of the character described, a valve chest, valve actuating means therein including movable cam means having a segment movable with relation thereto, and stop means co-operating with said segment to move it periodically upon movement of the cam means.

60 2. In engine mechanism of the character described, a valve chest, valve actuating means therein including movable cam means having a segment movable with relation thereto, and stop means co-operating with said segment to move it periodically upon movement of the cam means, together with control means for said stop means.

3. In reversible engine mechanism of the character described, a valve chest, valve actuating means therein including movable cam means having a segment movable with relation thereto, and stop means co-operating with said segment to move it periodically upon movement of the cam means, together with control means for said stop means under the influence of the engine reversing 75 mechanism.

4. In reversible engine mechanism of the character described, a valve chest, valve actuating means therein including movable cam means having a segment movable with relation thereto, and stop means co-operating with said segment to move it periodically upon movement of the cam means, together with control means for said stop means under the influence of the engine reversing mechanism and adapted to render said stop means inoperative at high speeds of the engine. 5

5. A single-expansion double-acting steam locomotive engine having a plurality of cylinders with their pistons, respectively of substantially equal diameters and equal strokes; for each cylinder, main steam distribution valve mechanism and steam portage controlled thereby and opening into the two ends of the cylinder; valve gear means operatively connected with said mechanisms for actuating the same in timed relation with the stroke of the pistons and set to effect a predetermined nominal or maximum normal cut-off of a given predetermined percentage value of the piston stroke which is substantially identical at both ends of each cylinder; the valve gear means having reversing apparatus for reversing the direction of operation of the locomotive; cranks to which the pistons are operatively connected, said cranks being angularly set one to another and the connecting means between the pistons and their cranks being thus positioned to assume relatively different angles at various points in the cycle of operation of the locomotive engine, whereby marked differences in the combined rotative effort of said plurality of cylinders considered together occur at different points in the cycle of operation of the locomotive engine, so that the combined rotative effort curve presents substantial differences between the high and low points thereof; mechanism for reducing the spread between some of the high and low points of the combined rotative effort, during the lower range of operating speeds of the locomotive, including means for altering the effective 10 cut-off point of said distribution valve mechanism at one end of one cylinder as compared with said predetermined normal cut-off of the distribution valve mechanism at the corresponding end of another cylinder without altering the total stroke of the valve mechanism; said means being 15 so arranged that the total work of the cylinders 20 may be increased to produce a higher average tractive power without lowering the true factor 25 of adhesion of the locomotive; and means for rendering said alteration of cut-off ineffective during the higher range of operating speeds of the 30 locomotive. 35

40 45 50 55 60 65 70 75

6. A single-expansion double-acting steam locomotive engine having a plurality of cylinders with their pistons, respectively of substantially equal diameters and equal strokes; for each cylinder, main steam distribution valve mechanism and steam portage controlled thereby and opening into the two ends of the cylinder; valve gear means operatively connected with said mechanisms for actuating the same in timed relation with the stroke of the pistons and set to effect a predetermined nominal or maximum normal cut-off of a given predetermined percentage value of the piston stroke which is substantially identical at both ends of each cylinder; the valve gear means having reversing apparatus for reversing the direction of operation of the locomotive; cranks to which the pistons are operatively connected, said cranks being angularly set one to 75

another and the connecting means between the pistons and their cranks being thus positioned to assume relatively different angles at various points in the cycle of operation of the locomotive engine, whereby marked differences in the combined rotative effort of said plurality of cylinders considered together occur at different points in the cycle of operation of the locomotive engine, so that the combined rotative effort curve presents substantial differences between the high and low points thereof; mechanism for reducing the spread between some of the high and low points of the combined rotative effort, during the lower range of operating speeds of the locomotive, including means for altering the effective cut-off point of said distribution valve mechanism at one end of one cylinder as compared with said predetermined normal cut-off of the distribution valve mechanism at the corresponding end of another cylinder without altering the total stroke of the valve mechanism; said means being so arranged that the total work of the cylinders may be increased to produce a higher average tractive power without lowering the true factor of adhesion of the locomotive; and means for obtaining a like effect by a similarly altered cut-off in reverse operation.

7. A single-expansion double-acting steam locomotive engine having a plurality of cylinders with their pistons, respectively of substantially equal diameters and equal strokes; for each cylinder, main steam distribution valve mechanism and steam portage controlled thereby and opening into the two ends of the cylinder; valve gear means operatively connected with said mechanisms for actuating the same in timed relation with the stroke of the pistons and set to effect a predetermined nominal or maximum normal cut-off of a given predetermined percentage value of the piston stroke which is substantially identical at both ends of each cylinder; the valve gear means having reversing apparatus for reversing the direction of operation of the locomotive; cranks to which the pistons are operatively connected, said cranks being angularly set one to another and the connecting means between the pistons and their cranks being thus positioned to assume relatively different angles at various points in the cycle of operation of the locomotive engine, whereby marked differences in the combined rotative effort of said plurality of cylinders considered together occur at different points in the cycle of operation of the locomotive engine, so that the combined rotative effort curve presents substantial differences between the high and low points thereof; mechanism for reducing the spread between some of the high and low points of the combined rotative effort, during the lower range of operating speeds of the locomotive, including means for altering the effective cut-off point of said distribution valve mechanism at one end of one cylinder as compared with said predetermined normal cut-off of the distribution valve mechanism at the corresponding end of another cylinder without altering the total stroke of the valve mechanism; said means being so arranged that the total work of the cylinders may be increased to produce a higher average tractive power without lowering the true factor of adhesion of the locomotive; means for obtaining a like effect by a similarly altered cut-off in reverse operation; and means for rendering said alteration of cut-off ineffective during the higher range of operating speeds of the locomotive.

75 8. A reversible steam engine having a pair of

cylinders one of which is a leading cylinder and the other a following cylinder in one direction of motion and vice versa in the opposite direction of motion, steam admission valve means for said cylinders having means for setting the same to produce a predetermined normal maximum cut-off the same for both ends of both cylinders, mechanism adapted to shorten the cut-off on the crank end and lengthen the cut-off on the head end of either cylinder as compared with the cut-off on the two ends of the other, and control means adapted to select, as between said cylinders, which shall have the modified cut-offs.

9. A reversible steam engine having a pair of cylinders one of which is a leading cylinder and the other a following cylinder in one direction of motion and vice versa in the opposite direction of motion, steam admission valve means for said cylinders having means for setting the same to produce a predetermined normal maximum cut-off the same for both ends of both cylinders, mechanism adapted to shorten the cut-off on the crank end and lengthen the cut-off on the head end of either cylinder as compared with the cut-off on the two ends of the other, and automatic control means actuated under the influence of the direction of motion of the engine to select the following cylinder and effect said altered cut-off on that cylinder only.

10. A reversible steam engine having a pair of cylinders one of which is a leading cylinder and the other a following cylinder in one direction of motion and vice versa in the opposite direction of motion, steam admission valve means for said cylinders having means for setting the same to produce a predetermined normal maximum cut-off the same for both ends of both cylinders, mechanism adapted to shorten the cut-off on the crank end and lengthen the cut-off on the head end of either cylinder as compared with the cut-off on the two ends of the other, control means adapted to select, as between said cylinders, which shall have the modified cut-offs, and means operative under the influence of shortening of the normal cut-off of the locomotive to render said mechanism inoperative.

11. A reversible steam engine having a pair of cylinders one of which is a leading cylinder and the other a following cylinder in one direction of motion and vice versa in the opposite direction of motion, steam admission valve means for said cylinders having means for setting the same to produce a predetermined normal maximum cut-off the same for both ends of both cylinders, mechanism adapted to shorten the cut-off on the crank end and lengthen the cut-off on the head end of either cylinder as compared with the cut-off on the two ends of the other, automatic control means actuated under the influence of the direction of motion of the engine to select the following cylinder and effect said altered cut-off on that cylinder only, and means operative under the influence of shortening of the normal cut-off of the locomotive to render said mechanism inoperative.

12. A simple multiple cylinder engine having admission valves for the cylinders, means automatically acting to effect a substantial differing power distribution to one cylinder as compared with another during a complete cycle when operating at late valve cut-off, and means automatically acting to effect equal and regular power distribution as to each cylinder at a reduced valve cut-off.

13. In a multiple cylinder locomotive, the com-

- 5 combination of cylinders, valve chests, valves, main steam passages, valve gear, a reverse gear controlling the valve gear in synchronous movement and including a reverse lever, means associated with the valves for effecting a difference in the cut-off as between cylinders and means associated with the reverse gear to determine which cylinder shall have the greatest cut-off, said last mentioned means automatically operating the first 5
- 10 mentioned means upon movement of the reverse lever.
14. In a locomotive, the combination of cylinders, valve chests, valve mechanism, main steam passages at the ends of the cylinders, valve gear, reverse mechanism for the valves, means associated with the valve mechanism for effecting an earlier cut-off on the steam passage at the crank end of either of the cylinders, and control means for determining which cylinder shall have the 10 early cut-off on the crank end.
15. In a locomotive, the combination of cylinders, valve chests, valve mechanism, main steam passages at the ends of the cylinders, valve gear, reverse mechanism for the valves, means associated with the valve mechanism for effecting an earlier cut-off on the steam passage at the crank end of either of the cylinders, and control means for determining which cylinder shall have the 15 early cut-off on the crank end, such control 20 means being under the influence of the reverse mechanism.
- 25 30
16. In a locomotive, the combination of cylinders, valve chests, main valve mechanism, main steam passages at the ends of the cylinders, valve gear, reverse mechanism, the valve mechanism being set to give approximately equal cut-off at both ends of the cylinders when the valve is in full travel, means controlling the valve mechanism to effect an earlier cut-off of the valve at 35 one end of a cylinder than at the other and control means for determining which cylinder shall have such earlier cut-off.
- 40
- 35 40
17. In a locomotive, the combination of cylinders, valve chests, main valve mechanism, main steam passages at the ends of the cylinders, valve gear, reverse mechanism, the valve mechanism being set to give approximately equal cut-off at both ends of the cylinders when the valve is in full travel, means controlling the valve mechanism to effect an earlier cut-off for the valve at one end of a cylinder and a later cut-off for the valve at the opposite end than the nominal cut-off for full travel, together with means for determining which cylinder shall have such altered 45
- 50 55
- 55 cut-off.
18. In a locomotive, the combination with the cylinders, main valves, valve chests, valve gear, and reversing apparatus operating all valves simultaneously and providing a full gear travel 60 of the valves of a predetermined normal maximum cut-off, of mechanism for increasing that normal cut-off at one end of a cylinder and reducing that normal cut-off at the other end of the cylinder, means for simultaneously retaining 65 the full gear cut-off on the other cylinder, control means for said mechanism and means associated with the reversing apparatus for initiating and discontinuing the action of said control means.
- 65
19. In a locomotive having cylinders, main 70 inlet valves, valve chests, and valve gear and
- reversing apparatus for operating the valves and providing a predetermined normal maximum operating cut-off; a movable cam actuated by said valve gear for operating a main inlet valve, said cam having a high and transition surface for holding the valve from the seat and a low surface for closure or seating of the valve and an intermediate surface to hold the valve from its seat beyond the normal point of closure. 5
20. In a locomotive having cylinders, main inlet valves, valve chests, and valve gear and reversing apparatus for operating the valves and providing a predetermined normal maximum operating cut-off; a movable cam means for operating a main inlet valve, said cam means having a high surface and a low surface respectively operating for opening and closure of said valve, a cam follower connected to said valve and positioned to ride on the cam surface, and a shiftable cam element providing for the cam follower to ride on the higher or lower cam surfaces for a greater distance at starting than for normal operation. 10
- 25 30
21. In a locomotive having cylinders, main inlet valves, valve chests, and valve gear and reversing apparatus for operating the valves and providing a predetermined normal maximum operating cut-off; a movable cam means for operating a main inlet valve, said cam means having a high surface and a low surface respectively operating for opening and closure of said valve, a cam follower connected to said valve and positioned to ride on the cam surfaces, a shiftable cam element providing for the cam follower to ride on the higher or lower cam surfaces for a greater distance at starting than for normal operation, means for shifting the cam element for starting into or out of the path of the cam follower and means resisting the placing of the shiftable cam element in position other than for normal 35 running operation of the locomotive. 40
- 35 40
22. In a locomotive having cylinders, main inlet valves and valve gear with reversing apparatus, movable cams actuated by the valve gear for operating the main inlet valves, the leading cylinder having approximately equal cut-offs at both ends of the cylinder, means associated with the following cylinder to effect an earlier cut-off on the crank end and a later cut-off on the head end with relation to the cut-off on the leading cylinder, and control means automatically operative upon reversal of the reversing apparatus for determining which cylinder shall have the altered 45 cut-offs. 50
- 50 55
23. In a limited cut-off steam engine having cylinders, main inlet valves, valve chests and valve gear for operating the valves and providing a predetermined normal maximum operating cut-off; a movable cam actuated by said valve gear for operating a main inlet valve, said cam having a high and transition surface for holding the valve from its seat up to the point of normal cut-off and a low surface for closure or seating of the valve and an intermediate surface to hold the valve from its seat beyond the normal point of closure, said intermediate surface operating to prevent the lifting of the valve from its seat before the normal point of admission. 60
